UNITED STATES PATENT OFFICE.

EDMUND G. ROEDIGER, OF JUNCTION CITY, KANSAS.

SAFETY-STIRRUP.

1,162,651.

Specification of Letters Patent.

Patented Nov. 30, 1915.

Application filed September 26, 1914. Serial No. 863,665.

To all whom it may concern:

Be it known that I, EDMUND G. ROEDIGER, a citizen of the United States, residing at Junction City, in the county of Geary and State of Kansas, have invented new and useful Improvements in Safety-Stirrups, of which the following is a specification.

The invention relates to stirrups, and more particularly to the class of safety stirrups. 10 The primary object of the invention is the provision of a safety stirrup wherein the foot will be freed therefrom in event of the rider being thrown from the horse.

Another object of the invention is the provision of a safety stirrup in which the tread piece is swingingly mounted to permit the opening of the stirrup on the unlatching of the tread piece.

A further object of the invention is the provision of a stirrup wherein the construction thereof permits the opening of the same so that the foot of the user will not become caught therein should the rider be thrown from the mount.

25 A still further object of the invention is the provision of a stirrup wherein the same is locked so as to obviate the possibility of the accidental opening thereof.

A still further object of the invention is 30 the provision of a safety stirrup which is simple in construction, reliable and efficient in its purpose, and inexpensive in manufacture.

With these and other objects in view, the 35 invention consists in the construction, combination and arrangement of parts as will be hereinafter fully described, illustrated in the accompanying drawing, and pointed out in the claim hereunto appended.

40 In the drawing:—Figure 1 is a side elevation of a stirrup constructed in accordance with the invention. Fig. 2 is a front elevation thereof. Fig. 3 is a vertical sectional view of the same.

45 Similar reference characters indicate corresponding parts throughout the several views in the drawing.

Referring to the drawing in detail, the stirrup comprises a yoke frame 5 carrying a

tread bar 6, which is connected to one limb 50 by means of a hinge 7 for swingingly supporting the said tread bar.

The tread bar at its end opposite the hinge connection is formed with spaced ears 8 which are adapted to enter slots 9 formed in 55 the other limb of the yoke frame 5 and opening through the free edge thereof, the ears 8 being engaged by means of a catch device hereinafter fully described.

Disposed against the limb of the yoke 60 frame 5 exteriorly thereof above the slots 9 is a slidable catch plate 10 formed with hooks 11 which are adapted to be brought into locking engagement with the ears 8 for the fastening of the tread bar 6 against 65 swinging movement. The plate 10 is formed with elongated guide slots 12 through which are passed guide rivets 13, the same being secured in the yoke frame 5 and serve to guide the plate 10 in its movement when 70 operated, in a manner presently described.

Pivottally mounted upon the limbs of the yoke frame 5 is a substantially inverted U-shaped trip bail 15 having an arm 16 provided with a slot 17 in which is engaged a 75 pivot 18 mounted in the plate 10, the bail being disposed at one side of the yoke frame 5 to bridge the foot when engaged in the yoke frame and resting on the tread bar 6 of the stirrup so that when the foot of the rider 80 rocks or becomes twisted in the stirrup the foot will contact with the bail 15 and a pressure will be exerted against the same so that the plate 10 will be shifted to unlatching position, thereby freeing the tread bar 10 so 85 that it will swing to open position to permit the foot to become freed from the stirrup. In this manner the foot will not become caught in the stirrup should the rider be thrown from the mount.

90 From the foregoing it is thought that the construction and manner of operation of the device will be clearly understood, and therefore a more extended explanation has been omitted.

95 What is claimed is:—

A safety stirrup comprising a yoke frame, a tread bar pivotally connected to one limb

of the frame, the said frame being formed in its other limb with notches, ears on the free end of the tread bar and received in the notches, a sliding latch plate mounted on the notched limb of the frame and having hook-like portions for engagement with the ears on the tread bar to lock the same closed, and a bail pivotally mounted upon the frame

and having a lever extension pivotally connected to the said plate.

In testimony whereof I affix my signature in presence of two witnesses.

EDMUND G. ROEDIGER.
